UNITED STATES PATENT OFFICE.

HUGO STOMMEL, OF ELBERON, NEW JERSEY.

TILE-GLAZING MACHINE.

1,163,117.

Specification of Letters Patent.

Patented Dec. 7, 1915.

Application filed September 11, 1913. Serial No. 789,229.

To all whom it may concern:

Be it known that I, HUGO STOMMEL, a citizen of the United States, residing in Elberon, county of Monmouth, and State of New Jersey, have invented a certain new and useful Tile-Glazing Machine, of which the following is a specification.

This invention is a machine for coating or glazing tiles, and the objects of the invention are: to simplify the construction, cheapen the cost of production, and secure increased efficiency both in the quality and quantity of the coated tiles, over that of the machines heretofore used.

One of the salient features of the invention consists in the employment of a laminated liquid conveyer, the base of which consists preferably of rubber, said conveyer being provided with a continuous longitudinal channel intermediate its edges. In this channel is positioned a suitable porous or absorbing medium, *e. g.*, cheese cloth for the coating solution. Externally of the absorbing medium is a perforated member of suitable material, *e. g.*, a celluloid band whereby a smooth uniform contact between the tiles and the conveyer is assured, said celluloid serving as a base or support for the external or top covering, preferably wire mesh of the conveyer.

A further feature of the invention consists of an extension or well in communication with the tank containing the coating solution. The greater portion of the conveyer is immersed in the solution contained in said well whereby it is charged with the solution and remains thus charged until brought into engagement with the tile to be coated, whereupon a pressure roll engaging the back of the tile forces the same against the conveyer, thus causing the coating solution to be squeezed out of the conveyer and deposited upon the face of the tile.

Another feature of the invention, and one of pronounced practical importance, consists in the accessibility of the working parts of the structure, the construction being such that the conveyer and its coöperating parts may be readily removed from the well for the purpose of cleaning or repairing the parts and without interfering with the tank or the driving mechanism of the conveyer.

Features of the invention other than those referred to, will be clear from the herein-after detailed description.

In the accompanying drawings I have

illustrated one practical embodiment of my invention. This embodiment is, however, to be understood as illustrative only, and not as defining the limits of the invention.

Figure 1 is a vertical longitudinal section through a machine embodying the present invention, said section to be taken substantially through the center of the machine, and certain parts thereof left in full in the interest of clearness. Fig. 2 is a vertical transverse section taken on line 2—2 of Fig. 1. Fig. 3 is a fragmental edge view of a certain conveyer which I employ illustrating the means whereby said conveyer is positively driven. Fig. 4 is a fragmental transverse section taken on the line 4—4 of Fig. 3. Fig. 5 is a perspective view of a portion of the solution containing illustrating means for regulating the amount of coating solution carried by the conveyer.

In said drawings, A designates a flexible liquid conveyer, stretched about a pair of rollers B and B', which rollers are revolvably mounted one above the other, in a frame work C. The frame work C is suspended for its greater portion in a narrow extension D, of a tank or container D' which tank and extension are mounted in any suitable form of standards, not shown. The frame suspension is effected by means of projecting arms c, integral with the frame, and adapted to be bolted, or otherwise secured, to the brackets d, mounted on the tank extension D. The roller B is mounted on the shaft E in fixed journals e, and the roller B' is mounted on the shaft E', carried by slidable journals e'. The tension on the conveyer A may be regulated by any means such as set screws f, which are threaded through the frame C and engaged with the upper faces of the slidable bearings e'. The shaft E' is kept properly lubricated by means of lubricant supply pipes F.

At both ends of each of the rollers B and B' and fixedly mounted on the shafts E and E' are sprocket wheels G and G', respectively. Around each pair of sprockets, on the respective sides of the roller, pass sprocket chains H, for the purpose of revolving the said rollers in timed relation, which rollers are operated by means of a belt, not shown, coöperating with the fixed and loose rollers I and I' mounted on short shaft E'', which is properly positioned in a bearing x', supported by the tank D', in alinement, and in end-abutting relation to

the shaft E. The short shaft E² operates the shaft E through clutch members U' and V'.

The conveyer A, for the proper operation of the machine should pass from one roller to the other, at substantially constant speed, and this is brought about by securing said belt along its edges to the sprocket chains H, said securing means being shown more particularly in Figs. 3 and 4. This securing of the edges of the belt to the sprocket chains occurs at fixed distances throughout the endless extent of the conveyer. Each of the means for fastening the conveyer to the chains consists in a screw J which passes through a washer j, through the conveyer A, through a spacing member j' and then threads into a top in the solid blocks h of each of the chains H. Manifestly, the turning of the fixed pulley I, on the shaft E², will rotate the sprockets G, with the result that the conveyer A is positively driven.

The tank D' is adapted to contain considerable depth of the tile coating or glazing fluid, and a corresponding depth is consequently maintained at all times in the extension D thereof. It will thus be apparent that the frame C is suspended in the solution, so that the conveyer A, in its travel about the supporting rollers B and B', will pass through the glazing fluid and will, when the machine is in operation carry a portion of said fluid up and over the roller B.

The tiles K to be glazed are fed to the liquid conveyer A on an endless apron L, which passes over a roller l, and are received and carried away after being coated by means of an apron L', passing about the roller l'.

A pressure roll N is preferably made of leather, rubber, or some other slightly cushioning material is provided, and is mounted in journals M for vertical adjustment in slideways m in the frame C. This is made by means of set screws n², threaded through the upper portion of the frame, and coöperating with springs O, in engagement with the under side of the journals. The rollers N and B are driven at substantially the same speed, by means of gears X and X'. The gear X is carried by short shaft n' in alinement, and in end-abutting relation to the shaft n, said shaft being mounted in a bearing x, preferably cast integral with the bearing x' which supports the shaft E². The inner end of the shaft n' has fixed thereto a clutch member V which coöperates with the clutch member U on the adjacent end of the shaft n.

I do not wish to restrict myself to the specific form of liquid conveyer herein shown; yet I have found a conveyer of the structure herein illustrated particularly well adapted to carry out the functions which it

is called upon to perform. This specific form is shown, more particularly, in Figs. 3 and 4. It embodies a base P of rubber or other slightly flexible material, and is provided within its edges with a channel p, 70 extending uninterruptedly around the conveyer. This channel p is for the reception of a plurality of layers of flexible porous or absorbent material, e. g., cheese cloth, which fills up the channel so that the top layer of 75 cloth is substantially flush with the thickest portion of the body P. Exterior of the body P, and over the porous material is a perforated sheet R of some fairly rigid material, e. g., celluloid, which perforated sheet 80 serves as a semi-rigid backing for the top covering of the conveyer. The conveyer has a top covering of gauze or fine mesh wire S. It will thus be manifest that, in passing through the solution the porous or 85 absorbent portion Q of the conveyer will take up a portion of said solution, and the same will be carried upon the rotation of the conveyer to the supporting roller B, and over said roller, to be applied to the under side of the tile as it passes between said conveyer and the pressure roll M. While, however, the tile is in this position between the conveyer and the pressure roller, the pressure of said roller causes the tile to be 90 pressed slightly down upon the liquid conveyer with the result that the coating solution resident in the porous portion Q thereof, is squeezed out through the perforated sheet R and through the wire S into intimate contact with the under face of the tile 95 for the purpose of applying the coating thereto.

Another feature of the invention is the embodiment of a wiper which is employed, 1 more particularly, for the purpose of uniformly distributing the solution carried by the conveyer throughout the extent thereof. This wiper T is formed preferably of fiber or some other material which will not tend to scratch or destroy the conveyer, and is, in length, equal to the width of said conveyer. It is attached to an inner face of the extension D of the tank near the top edge thereof by means of bolts t'. Wiper T is thus positioned at right angles to the direction of travel of the conveyer and is provided with an inwardly extending flange t² which is adapted to engage with the exterior face of said conveyer. The free edge of the wiper may be brought into desired contact with the conveyer by means of adjustable screws t which are threaded through tank extension D, and engaged with the back of wiper. The operation of the member T will be apparent from the foregoing description, it being clear that the free edge thereof in engagement with the exterior surface of the conveyer, will uniformly distribute the coating solution carried thereby.

A salient feature of this invention resides in the simplicity and accessibility of the parts thereof. For many reasons, it is desirable that the frame C, and the parts co-operating therewith be so mounted on the tank extension D that said frame and component parts may be lifted out *en masse* for the purpose of cleaning, etc. For this reason, the shaft n, which carries the pressure roll and the shaft E, on which the roller B is fixed, terminate on the outside of the frame and on the driving side thereof, in the clutch members U and U' respectively. The ends of the shafts n' and E², which abut the adjacent ends of the shafts n and E, are provided with clutch members V and V', complementary to clutch members U and U' respectively. It will thus be seen that, when it is desired to detach the frame C and the tank extension D, it is only necessary to remove the bolts e' and turn the shafts n and E into such position that the male clutch members of the clutches U, U' and V, V' are vertically disposed whereupon the entire frame may be lifted bodily out of the solution.

It will be manifest from the foregoing description that my invention is of an extremely simple and novel character, none of the mechanism of which is apt to get out of order, or need careful attention, the device being highly efficient in its operation and producing much superior results to the machines now in use.

Having thus fully described the invention, what I claim as new, and desire to secure by Letters Patent is:—

1. In a tile coating machine, an endless liquid conveyer belt embodying a base member, a plurality of plies of absorbent material and a non-absorbent facing superimposed upon said base member, and secured against shifting relatively thereto, and means for charging said conveyer belt with a tile glazing solution.

2. In a tile coating machine, the combination of an endless liquid conveyer belt embodying a flexible base, absorbent mate-

rial exterior of said base, and a non-absorbent facing covering said absorbent material and secured against shifting relatively thereto, and means for introducing a tile glazing solution into the absorbent material.

3. In a tile coating machine, an endless liquid conveyer belt embodying a flexible base, absorbent material exterior of said base whereby a tile coating solution may be absorbed and carried by the conveyer, a perforated, semi-rigid band exterior of said absorbent material, and a fine mesh top covering for the conveyer, all of said parts being secured together against relative longitudinal or transverse movement.

4. In a tile coating machine, an endless liquid conveyer embodying a flexible base provided with a longitudinal channel intermediate its edges, absorbent material in said channel, and means for saturating said absorbent material with a tile coating solution whereby said absorbent material serves as a carrying medium of the conveyer.

5. In a tile coating machine, an endless liquid conveyer embodying a flexible base provided with a longitudinal channel intermediate its edges, absorbent material positioned in said channel, means for saturating said absorbent material with a tile coating solution whereby said absorbent material serves as a carrying medium of the conveyer, a perforated top covering for said conveyer means coöperating with the conveyer whereby a tile brought intermediate said members is pressed against the latter for the purpose of squeezing the coating solution out of the absorbent portion of the conveyer and depositing it upon the tile.

6. In a tile coating machine, an endless conveyer belt having non-coating edges, and a longitudinally laminated coating portion intermediate the non-coating edges, said laminated portion embodying absorbent material.

HUGO STOMMEL.
